UNITED STATES PATENT OFFICE.

FRED BÜTTLER, OF TYNDALL, SOUTH DAKOTA.

DESIGN FOR A WATCH-FOB.

47,131.

Specification for Design.

Patented Mar. 23, 1915.

Application filed December 10, 1914. Serial No. 876,581. Term of patent 7 years.

To all whom it may concern:

Be it known that I, FRED BÜTTLER, a citizen of the United States, residing at Tyndall, in the county of Bonhomme and State of South Dakota, have invented a new, original, and ornamental Design for Watch-Fobs, of which the following is a specification, reference being had to the accompanying drawing, forming part thereof.

The figure is a view in elevation of a watch fob, showing my new design.

I claim:

The ornamental design for a watch fob, as shown.

FRED BÜTTLER.

Witnesses:

GILBERT N. FITES,
LE ROY HIXSON.
